(57) **CLAIM**

The ornamental design for a label sheet, as shown and described.

DESCRIPTION

FIG. 1 is a top plan view of a label sheet of the present invention;

FIG. 2 is a left side elevational view thereof; the right side elevational view being a mirror image thereof;

FIG. 3 is a front end elevational view thereof; the rear end elevational view being a mirror image thereof;

FIG. 4 is a bottom plan view thereof;

FIG. 5 is an enlarged cross-sectional view taken on line 5—5 of FIG. 1;

FIG. 6 is a top plan view of a second embodiment thereof; FIG. 7 is a left side elevational view of the embodiment of FIG. 6; the right side elevational view being a mirror image thereof;

FIG. 8 is a front end elevational view of the embodiment of FIG. 6; the rear end elevational view being a mirror image thereof;

FIG. 9 is a bottom plan view of the embodiment of FIG. 6; and,

FIG. 10 is an enlarged cross-sectional view taken on line 10—10 of FIG. 6.
